UNITED STATES PATENT OFFICE.

JOHN M. FEDDERS, OF BUFFALO, NEW YORK, ASSIGNOR TO FEDDERS MANUFACTURING COMPANY INC., OF BUFFALO, NEW YORK, A CORPORATION OF NEW YORK.

RADIATOR CORE.

Application filed July 6, 1926. Serial No. 120,608.

This invention relates to a core which is more particularly designed for use in radiators which are used in connection with gas engines for cooling the water employed for preventing excessive heating of the engine, particularly radiators of this character which are employed on automobiles and other automotive vehicles, such as motor boats, aeroplanes and the like.

It is the object of this invention to provide a core for such radiators which will yield a greater radiating efficiency for a given amount of metal, which can be manufactured expeditiously and economically and which is strong and durable and not likely to get out of order when subjected to the vibrations of the car on which the same is mounted.

In the accompanying drawings:—

Figure 1 is a fragmentary front elevation of a radiator core embodying one form of my invention.

Figure 2 is a vertical section taken on the correspondingly numbered line in Figure 4.

Figure 3 is a top plan view of a portion of the radiator core containing my improvements, as shown in Figs. 1 and 2.

Figure 4 is a horizontal section taken on line 4—4 Fig. 2.

Figures 5 and 6 are perspective views of one section of a radiator unit made in accordance with the construction shown in Figs. 1 to 4.

Figure 7 is a fragmentary front elevation of a radiator core containing my invention but slightly modified as compared with the construction shown in Figs. 1 to 6.

Similar characters of reference indicate like parts in the several figures of the drawings.

In its general organization, this radiator core as shown in Figs. 1 to 6 comprises a plurality of water passages 10 which in the instant case are arranged vertically, and a plurality of air tubes 11, 12, which are arranged between said water passages.

Each of the water passages 10 is formed between the opposing sides of two sheet metal strips so that this passage is arranged vertically. Each of these sheet metal strips is preferably made of very thin copper or similar metal and is provided at its opposite vertical edges with laterally off-set flanges 13, which are adapted to engage with corresponding flanges 13, of a companion

strip, while the intermediate part or body of this strip recedes and forms an upright wall 14 which is spaced apart from the companion wall 14 of an adjacent metal strip and forms with the same an upright water passage, conduit, or pipe, which is flattened and extends with its length fore-and-aft of the radiator core.

The off-set flanges 13, 13 at opposite longitudinal edges of the two cooperating strips of metal are securely connected with each other by soldering or otherwise to form a leak-tight joint between the same for preventing the escape of water from the core.

At intervals, each of the sheet metal strips is provided with laterally projecting loops which are so constructed that the metal of the same is integrally connected with the walls of the water passages, and form a plurality of air tubes between adjacent water passages, whereby the heat which is conducted from the walls of the water passages to these air tubes is absorbed by the air passing through the same, and thereby operates to reduce the temperature of the water which is passing through the water passages. Although these air tubes may be of various forms in cross section, the same are preferably of hexagonal form as shown in Figs. 1 and 2.

Each of these laterally projecting loops of a metal strip is bent to form one complete air tube 11 of hexagonal form which has two of its opposing flat sides arranged horizontally at the top and bottom of each tube thereof. On that longitudinal side of each air tube 11 next to the companion wall 14 and flanges 13 of the respective air tube, the loop forming a complete air tube 11 is connected by means of two webs 15—15, with the wall 14 and flanges 13 of the respective metal strip so as to be connected integrally therewith, as shown in Figs. 1 and 2. On the opposite longitudinal side of each complete air tube 11, the same is provided with a bead, the opposite ends of which are provided with laterally projecting lugs 16 which engage with the off-set flanges 13 on the opposing wall of an adjacent water tube; while the intermediate edge portion of this bead is provided with a longitudinal recess 17 which receives the laterally bulging or receding wall 14 of this last mentioned water tube.

- In the assembled position of a plurality of units of this character, the air tubes of one strip are intercalated with the air tubes of an opposing strip of an adjacent water tube and the air tubes of these two strips engage each other at their upper and lower flat sides or facets; and the longitudinal bead of each of these strips engages with the wall and off-set flanges of the other strip.
- 10 The joint between the webs 15—15 of each loop is closed by solder so as to form a leak-tight joint there-between, and the beads of the air tubes on one strip are connected with the wall of an opposing strip, and the several air tubes of two adjacent units are connected with each other by solder, thereby securely connecting the several parts of the radiator core and not only preventing the same from leaking, but also forming a very
- 15 20 rigid structure which is not likely to give way and cause leakage under severe strains.
- When two units are thus assembled, the complete air tubes 11 are arranged in a vertical row and these in connection with the opposing walls of two adjacent strips, form two vertical rows of half tubes 12, adjacent to the outer sides of the water tube walls. When, however, a plurality of such units are assembled, the half air tubes on opposite
- 25 30 35 sides of each water tube present the appearance of complete air tubes, so that a radiator core when viewed from the front, as shown in Fig. 1, presents a honey-comb appearance in which each of the cells is of hexagonal form.
- In order to preserve the hexagonal appearance of the several cells of the radiator core and still permit cross circulation of air between the several air tubes for promoting the cooling effect of the same, each of the air tubes only engages the opposite ends of its upper and lower sides with the corresponding parts of adjacent air tubes, as shown at 18, but the intermediate parts 19 of the upper and lower sides of the air tubes are recessed or offset inwardly relative to the end portions thereof, as shown in Figs. 2, 3, 4 and 5, whereby horizontal transverse air conduits are formed between adjacent air tubes of both strips, which provide a free circulation of the air cross-wise through the radiator core, and thus aid in equalizing the cooling effect and obtaining the maximum efficiency of the core.
- 40 45 50 55 60 65 If desired, the loops which project laterally from each sheet metal strip at intervals in its length, may be so constructed that they produce more than one vertical row of air tubes in cooperation with similar loops formed on the opposing strip of an adjacent water passage wall. For example, as shown in Fig. 7, the loops on the opposing metal strips of their adjacent water tubes are so constructed that they produce three vertical tiers or columns of complete air tubes 20, 21,

21, each of these tubes being of hexagonal form in cross-section. In this construction, each of the sheet metal strips has its water passage wall 22 and the off-set flanges 23 at opposite ends thereof made of zig-zag form, so that the facets of this strip form some of the facets of the air tubes.

In the preferred construction, alternate summits of each of these sheet metal strips are provided with loops and beads which project laterally therefrom. Each loop has its extremity shaped to form a complete air tube 20, one longitudinal side of which is connected by integral webs 24 with the adjacent summit of the wall 22 and flanges 23 of the respective strip, so that this loop in effect is a continuation of the strip; and each of the beads is composed of two plies 25, the outer edges of which are connected with each other while the inner edges are connected respectively with the sections of the sheet metal strip on opposite sides of its summit.

In the assembled position of two adjacent strips having such alternate loops and beads, the upper and lower facets of the complete tubes 20 engage with each other, and the longitudinal side of each complete tube 20 engages with the outer edge of the bead on the opposing strip, so as to form two tiers of complete built-up air tubes 21, on opposite sides of the center row of integral air tubes 20, each of these built-up air tubes being made up by two facets of one of the strips, the adjacent web and bead associated with the respective facets of the strip, one of the inner facets of the complete air tube 20 on the respective strip, and one of the outer facets of the complete tube formed on an opposing strip of an adjacent water passage.

When a plurality of such strips are assembled, as shown in Fig. 7, the same are united with each other at their front and rear edges by means of solder so as to close the joints between the pairs of strips forming water tubes, also the webs which connect the complete air tubes with the walls and flanges of the strips and also the connection between the several air tubes with each other and with the beads on the walls and flanges, so as to form a rigid structure, the several parts of which will not become displaced under severe usage.

Both forms of my invention herein described and shown in the drawings, provide the maximum radiating surface for the amount of metal which is used in the construction of the core. The same also permits of a very effective flow of air through the radiator core for carrying away the heat of the water by convection, and the same is also of such a construction that the strips can be readily formed economically and expeditiously by machinery and assembled

with each other for producing complete radiator cores without involving undue cost.

I claim as my invention:

1. A radiator core having a plurality of water passages and a plurality of air tubes arranged between said water passages, each of said water passages having opposing walls formed by two strips of sheet metal which have their opposite longitudinal edges engaging one another and their walls intermediate of said edges spaced from each other, and each of said strips being provided at intervals with laterally projecting loops forming air tubes, and the air tubes of one of said strips being arranged in the space between similar air tubes of an adjacent strip.

2. A radiator core comprising a plurality of water passages and a plurality of air passages arranged between the water passages, each of said water passages being formed between two sheet metal strips provided with off-set flanges at their longitudinal edges which engage each other while their walls intermediate of said edges are spaced apart, and each of said strips being provided at intervals with laterally projecting loops forming air tubes, each tube being integrally connected by webs on one of its longitudinal sides with one strip and provided on its opposite longitudinal side with a bead, the ends of each bead being provided with lugs, and the intermediate part thereof being provided with a recess, said lugs and recess engaging with the offset flanges and the wall of an adjacent strip.

3. A radiator core comprising a plurality

of water passages and a plurality of air passages arranged between the water passages, each of said water passages being formed between two sheet metal strips provided with off-set flanges at their longitudinal edges which engage each other while their walls intermediate of said edges are spaced apart, and each of said strips being provided at intervals with laterally projecting loops forming air tubes, the tubes of each strip being complete and arranged between similar tubes of an adjacent strip and forming therewith partial air tubes which alternate with the complete tubes.

4. A radiator core comprising a plurality of water passages and a plurality of air passages arranged between the water passages, each of said water passages being formed between two sheet metal strips provided with off-set flanges at their longitudinal edges which engage each other while their walls intermediate of said edges are spaced apart, and each of said strips being provided at intervals with laterally projecting loops forming air tubes, and the air tubes of one strip being arranged between the air tubes of an adjacent strip, and the air tubes of one strip having its end portion engaging with the corresponding end portions of an air tube of an adjacent strip, while the intermediate parts of said air tubes are spaced apart to form transverse air passages therebetween.

In testimony whereof I, hereby affix my signature.

JOHN M. FEDDERS.
